US00D748748S

(12) **United States Design Patent**
Van Alen et al.

(10) **Patent No.:** **US D748,748 S**
(45) **Date of Patent:** **** Feb. 2, 2016**

(54) **ATHLETIC STICK HEAD**

(71) Applicant: **PlusOne Sports, LLC**, Ipswich, MA (US)

(72) Inventors: **Alex Van Alen**, Ipswich, MA (US); **Douglas G. Sabin**, Marblehead, MA (US); **Michael Tintzman**, Malden, MA (US); **William Liteplo**, Middleton, MA (US)

(73) Assignee: **PlusOne Sports, LLC**, Ipswich, MA (US)

(**) Term: **14 Years**

(21) Appl. No.: **29/490,692**

(22) Filed: **May 12, 2014**

(51) LOC (10) Cl. **21-02**

(52) U.S. Cl.

USPC **D21/722**

(58) **Field of Classification Search**

USPC **D21/722, 724**

CPC **A63B 59/02; A63B 49/06; A63B 65/12;**

A63H 33/18

(57) **CLAIM**

The ornamental design for an athletic stick head, as shown and described.

DESCRIPTION

FIG. 1 is a top perspective view of a first embodiment of an athletic stick head;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is a bottom perspective view thereof.

The dashed lines shown illustrate portions of the athletic stick head that form no part of the claimed design. The dotted lines shown in FIGS. 1 and 2 represent the bounds of the claimed design.

1 Claim, 8 Drawing Sheets
